Inventor:
John Petty
by Francis J. C. Lamber
his Attorney.

UNITED STATES PATENT OFFICE.

JOHN PETTY, OF LEBANON, PENNSYLVANIA.

DESK FILE.

Application filed May 21, 1921. Serial No. 471,517.

To all whom it may concern:

Be it known that I, JOHN PETTY, a citizen of the United States of America, and resident of the city and county of Lebanon, in the State of Pennsylvania, have invented a certain new and useful Improvement in Desk Files, of which the following is a true and exact description, reference being had to the accompanying drawings, which form

10 a part thereof.

My invention relates to desk files and has for its object to provide such a file with a series of manually operative signals, each displayable at the rear end of the file and by 15 means of which selected individuals will have their attention called to the fact that the file contains papers which require their consideration.

The desk file is of a usual tray-like form 20 with a rear wall and preferably provided with a series of flaps or leaves forming compartments for papers and bearing distinguishing markings corresponding to the signals which are selectively displayed on 25 the rear face of the rear wall.

The nature of my invention will be best understood as described in connection with the drawings in which—

Figure 1 is a perspective view of my im- 30 proved desk file.

Figure 2, a longitudinal section on line 2—2 of Fig. 3, and

Figure 3 a cross section on line 3—3 of Fig. 2.

35 A indicates the desk file tray of familiar construction. It is made up of sheet metal and has a bottom A', tapered sides A², A², and a rear wall A³ on the inner face of which is secured a plate B having outwardly extend-

40 ing flanges B', B², which support the rods C, C, which pass through perforations f, f, in the rear edges of the flaps or leaves F, F', etc., which separate the compartments of the file. As shown, the flaps F, F', etc. are

45 numbered consecutively by two sets of numbers one reading from the front and the other from the back of the file and each flap also has inscribed upon it other compartment designations similarly readable.

50 Along the top of the rear wall and, as shown, secured to the flange B' I provide a

series of hinge plates D carrying hinge pins D' on which are pivoted a series of flaps E', E², etc., the hinge being so located that the flaps when turned forward will rest on top 55 of flange B' as shown at E', E², Fig. 1 and when turned backward will hang down over the rear face of the rear wall as shown at E⁴, Figs. 1 and 2.

Each flap E', E², etc. has a signal, preferably a number displayed on each side of it, one readable from the front when the flap is turned forward and one from the back when the flap is turned backward, and each signal or number corresponds to the 65 signal or number designating one compartment of the file.

In use, the flaps E', E², etc. are normally turned inward. The occupant of the desk on which the file rests places documents in 70 the proper compartments of the file and when he desires to call any of such documents to the attention of the person whose duty it is to remove and properly dispose of them he turns the flap E', E², etc. corresponding to the file compartment containing 75 such papers, backward so that it serves as a signal notifying the proper person to remove the designated papers.

Having now described my invention, what 80 I claim as new and desire to secure by Letters Patent is:

1. A desk file having a rear wall in combination with a series of manually operable call signals secured on said rear wall. 85

2. A desk file comprising a tray having a rear wall, in combination with manually operable means for displaying on the outside of said rear wall any of a series of call signals. 90

3. A desk file comprising a tray having a rear wall in combination with a series of signal flaps hinged along the top of said wall and separately rotatable from a normal forwardly extending position to a position in 95 which they extend down over the outer face of the rear wall.

4. A desk file comprising a tray having a rear wall in combination with a series of signal flaps hinged along the top of said 100 wall and separately rotatable from a normal forwardly extending position to a position

in which they extend down over the outer face of the rear wall, said flaps having similar signal markings on both sides thereof.

5. A desk file comprising a tray having a rear wall in combination with manually operatable means for displaying on the out-

side of said rear wall any of a series of call signals and a series of compartments supported on the tray having designating marks corresponding to the different call signals.

JOHN PETTY.
